UNITED STATES PATENT OFFICE.

GEORGE HENRY LAYNG, OF SAULT STE. MARIE, CANADA.

NUT-LOCK.

SPECIFICATION forming part of Letters Patent No. 734,577, dated July 28, 1903.

Application filed December 5, 1902. Serial No. 133,990. (No model.)

To all whom it may concern:

Be it known that I, GEORGE HENRY LAYNG, railway agent, a subject of the King of Great Britain, residing in the town of Sault Ste. Marie, in the district of Algoma, in the Province of Ontario, Canada, have invented certain new and useful Improvements in Nut-Locks, of which the following is a specification.

10 My invention relates to improvements in nut-locks; and the object of my invention is to more particularly design a nut-lock that can be easily and rapidly attached to a suitable base; and it consists, essentially, of a locking-bar provided with two **U**-shaped rivet-slots in each of which operates a stout pin which may be secured to one of the fish-plates or else to a separate base-plate. The said locking-bar is provided on its under side 15 with recesses which are designed to engage with the nuts of the bolts attaching the fish-plates to the rails and prevent same from turning, as hereinafter more particularly explained.

20 Figure 1 is a side elevation of my nut-lock attached to a fish-plate joining the adjacent ends of two rails. Fig. 2 is an end elevation of my nut-lock and rails to which same is attached, showing the nut-lock in normal position. Fig. 3 is an end elevation of my nut-lock and rails to which same is attached, showing said nut-lock out of engagement with the nuts it is designed to lock. Fig. 4 is a vertical section through the rail and fish-plate 25 for same, showing the locking-bar secured to said fish-plate. Fig. 5 is a side elevation of a portion of an alternative form of the locking-bar.

In the drawings like letters of reference indicate corresponding parts in each figure.

A represents the two rails, which are secured together by the bolts B and fish-plates C.

In manufacturing my nut-lock I preferably provide same with a base-plate D of its own, 45 which is of course manufactured so as to be placed adjacent one of the fish-plates and held thereagainst by means of the nuts E on the bolts B.

F is the locking-bar, provided with two **U**-shaped slots G, in which operates a stout pin H, secured to the base-plate D. In case the locking-bar F should be in the dotted posi-

tion shown in Fig. 1 if a train were moving in the right-hand direction the front wheels of same would strike against said locking-bar 55 and move same down in the direction indicated by arrow with tail to position shown in full lines. As the under side of the said locking-bar is provided with a suitable number of recesses I, which are designed to closely 60 fit the nuts E, it will be seen that when said locking-bar is in normal position said nuts are prevented from turning. From Figs. 2, 3, and 4 it will be noticed that I preferably taper the locking-bar F, as shown, although 65 I do not confine myself to so constructing same. As the wheel J moves toward the spectator same strikes the locking-bar F, and as same is wedge-shaped same is forced down into position shown in Figs. 1, 2, and 70 4 and wedged tightly between the said stout pins and the base-plate. It will be noticed that the stout pins H are provided with broad heads O, which prevent said pins from moving out of the said **U** shaped slots. I of 75 course do not confine myself to the construction shown of said stout pins nor to the manner shown for securing same to their supports.

P is any suitable lip by means of which the 80 locking-bar can be raised up or down by hand. It will be noticed that the said locking-bar is provided with a suitable number of recesses I, so that no matter in what direction the said locking-bar may be operated 85 it will engage with the nuts E and lock same.

If desired, I may attach my locking-bar F directly to one of the fish-plates, as shown in Fig. 4.

If desired, I may provide the recesses I with 90 suitable flanges i, thus increasing the area of said locking-bar in contact with the nuts E.

My nut-lock is preferably secured at the outside of the rail.

I preferably manufacture my locking-bar 95 wedge-shaped, as this construction prevents rattling and has also a tendency to retain the locking-bar in its normal position.

It will be noticed from Fig. 1 that the **U**-shaped slots are constructed in the locking-bar in the same position in which the ordinary letter "**U**" is ordinarily printed on a page.

The lower corners a of the recesses I are

rounded, as shown, so that when the locking-bar F is moved so as to lock the nuts the sides of same may be moved as closely as possible to the engaged sides of nuts and prevent any loosening of same.

What I claim as my invention, and desire to secure by Letters Patent, is—

1. A nut-lock comprising a locking-bar provided with a suitable number of recesses in its under side, the sides of which recesses are designed to engage with the sides of nuts to be locked and lock same, the said locking-bar being further provided with two U-shaped slots, and a stout pin operating in each of said U-shaped slots, the said stout pins being designed to be secured to a base through which the bolts of the nuts pass, and against which the nuts are jammed.

2. A nut-lock comprising a locking-bar, tapered from its upper end to its lower end, provided with a suitable number of recesses in its under side, the sides of which recesses are designed to engage with the sides of nuts to be locked and lock same, the said locking-bar being further provided with two U-shaped

25

slots, and a stout pin operating in each of said U-shaped slots, the said stout pins being designed to be secured to a base through which the bolts of the nuts pass, and against which the nuts are jammed.

30

3. A nut-lock comprising a locking-bar, tapered from its upper end to its lower end, provided with a suitable number of recesses in its under side, the sides of which recesses are designed to engage with the sides of nuts to be locked and lock same, the said locking-bar being further provided with two U-shaped slots; a stout pin operating in each of said U-shaped slots, the said stout pins being designed to be secured to a base through which the bolts of the nuts pass, and against which the nuts are jammed, and a lip attached to said locking-bar to enable same to be moved.

35

In testimony whereof I have signed my name to this specification in the presence of 45 two subscribing witnesses.

GEORGE HENRY LAYNG.
